ERNEST CANNING, OF SYDNEY, NEW SOUTH WALES, AUSTRALIA.

PAPER-SETTING YOKE IN TYPEWRITING MACHINES.

1,411,707.

Specification of Letters Patent. Patented Apr. 4, 1922.

Application filed May 9, 1921. Serial No. 463,012.

To all whom it may concern:

Be it known that I, ERNEST CANNING, a subject of the King of Great Britain and Ireland, residing at Sydney, county of Cumberland, and State of New South Wales, Australia, have invented certain new and useful Improvements in Paper-Setting Yokes in Typewriting Machines, of which the following is a specification.

10 In typewriting machines in present use, the paper is held snug on the platen cylinder during writing, by means of a yoke bar which bears down upon it above the impression line on which the type strikes. This 15 yoke bar is usually indexed to facilitate the tracing of positions for corrections on the written lines, and heretofore it has always been carried on a pair of swing arms centered rearward of the cylinder face and 20 mounted to permit the bar to be swung upward and backward over the platen cylinder to offer clearance for insertion or withdrawal of paper. This arrangement has proved to be an awkward one, more particularly when 25 the machine is used in the modern "billing" method, that is when a long billing sheet is set in writing position and separate invoice sheets, individual to the entries on the billing sheet, are required to be placed in front of 30 or behind the billing sheet with an interleaf sheet of carbon paper to carry through the entries as manifold, copies on to the rear sheet, and to be withdrawn as the respective 35 entries are completed whilst leaving the partially filled billing sheet retained in writing position on the platen cylinder. The yoke must be lifted at the completion of the writing of each entry and a new invoice sheet inserted behind the billing sheet, with a carbon paper interleaf, to take the next account.

In this lifting movement the yoke is swung back over the cylinder, and in doing so comes in the way of the fall of the paper and makes withdrawal and insertion of invoice 45 sheets and carbon interleaves very inconvenient, snudging and "treeing" of the sheets being consequently a common occurrence.

To facilitate the insertion and withdrawal of invoice sheets and carbon interleaves behind or in front of the billing sheet, I mount the yoke bar on swing arms which are centered in front of the platen cylinder, so that the yoke bar when being closed down to set the paper against the platen cylinder swings 50 back from the front of the machine towards the platen cylinder and bears upon it

a little above the type impression line. In this improved arrangement, the yoke bar when swung forward to clear the paper, takes up a position in which it is not in the way of the typist's manipulations as the upper aspect of the platen cylinder is left wholly free, and the typist is enabled therefore to make the change of sheets necessary without any inconvenience with maximum 65 rapidity, and without risk of defacing or mutilating either billing sheet, invoice sheet, or carbon interleaves.

The brackets on which the yoke bar swing arms are centered are mounted on the cylinder carriage and set as close as practicable to the cylinder ends in order to leave maximum clearance for access to and operation of the paper feed and other mechanism which is located at the ends of the cylinder 70 carriage.

In the accompanying drawing, Fig. 1 is a fragmentary perspective view showing the platen cylinder of a typewriting machine and the carrier frame elements in dotted 75 lines, with the attachment in which the present invention consists shown in full lines. In this view is also indicated a forward portion of a known typewriter machine, for the purpose of showing the manner in which location of positions on the yoke bar scale, for 80 corrections is indicated;

Fig. 2 is a corresponding end elevational view.

The platen cylinder 10 is mounted in the usual way on the frame brackets 11, said brackets being provided with a back beam 12 to carry the fall of the paper, or otherwise supporting a smooth plate to perform the same function of carrying the fall of the 95 paper 13 as the writing progresses and the sheet is traversed over the platen cylinder. 14 is a yoke bar which is scaled and figure indexed on its forward side to facilitate identification of position of letters incorrectly struck on the paper 13. The striking position of the keys is indicated by the pointed mark 15 on the nose portion of the cover casing 16 which protects the type bars and type assembly. 17-17 are rubber or 100 composition rollers adapted to rotate freely on the bar 14 as the paper 13 is traversed past it whilst the bar is held down against the paper to maintain the surface flat against the platen cylinder during the typing operation, that is the position shown in full lines 105 in Fig. 2. The yoke bar 14 is of cylindrical

section with the face portion flattened to carry the scale and figuring. The ends of the bar 14 are fixed to cranked swing arms 18 and 19. These arms are centered at 5 20—20 on pivot pins which are fixed in detachable bracket arms 21—21. These bracket arms are shaped to set in between the usual attachments on the frame members 11 so as not to interfere with the 10 standard elements of the machine and they are fixed in this position by means of grub screws 22. The cranked arms 18 and 19 are endowed with a snap over action by means of helical springs 23—23 set in tension. These springs are anchored back to fixed pins 24 on the frames 11 and are looped to holes 25 in the inbent portions of the cranked arms 19. They function to hold the cranked arms 18 and 19 and consequently 15 20 the bar 14 either fully backward bearing down on the paper and holding it on the platen cylinder in writing position as shown in the full lines (Fig. 2), or fully forward so as to hold the bar 14 clear to offer freedom 25 for manipulation of billing sheets and the invoice sheets and carbon interleaves, as indicated by the dotted lines in Fig. 2. The change of position is readily effected by the typist, a touch movement being sufficient to 30 throw the bar 14 forward or backward as required, the springs 23—23 prevent the bar standing in any intermediate position.

In operation, the billing sheet 13, which is usually a long sheet, is inserted in writing 35 position in the usual way, with a carbon interleaf and an invoice sheet in front of it or behind it. When the necessary entry for that invoice sheet has been typed the bar 14 being thrown backward to the position 40 shown in full lines in the drawings during this operation so as to hold the three thicknesses of paper set flat over the face of the platen cylinder, the bar 14 is pulled forward (towards the typist) to the position shown 45 in the dotted lines in Fig. 2. The papers will then tend to assume the position shown in the light dotted lines in Fig. 2. The cylinder being now manipulated by means of the milled wheel 30, the invoice sheet is 50 removed, and a new invoice sheet is placed

at proper distancing from the previous writing on the billing sheet, the carbon interleaf replaced, and the cylinder rotated by the milled cap 30 until the new writing position is attained. The bar 14 is now thrown forward so as to flatten back the sheets over the platen cylinder to the writing position shown in the full lines, and work proceeds as before. 55

The time of the typist is thus economized 60 and a great convenience is attained in the placing of the invoice sheets and carbon interleaves in proper position in front of or behind a billing sheet, and in the withdrawal 65 of the invoices after writing, with the security that none of the papers will be defaced or mutilated in this manipulation.

What I claim as my invention and desire to secure by Letters Patent is:—

1. The combination with the platen cylinder and its carrier frame in a typewriting machine of a paper setting yoke comprising a bar arranged in parallel relation to the cylinder axis and supported at its ends on pivotal arms which are centered at points 70 forward of the platen cylinder and are spring retained, so that in the release position the bar comes forwardly and leaves the upper aspect of the platen cylinder clear for the manipulation of papers, and so that 80 in the writing position the bar is held resiliently, bearing backward upon the paper upon the platen cylinder.

2. A paper setting yoke for a typewriting machine having points of pivotal support 85 on which it may be swung backwardly to contact with the platen cylinder and forwardly towards the operator to clear the upper aspect of the platen cylinder, the pivotal points of support being located at the 90 near side of the platen cylinder and springs disposed to pull the yoke to full forward and to full backward position and said bar being indexed on the face of it which is visible to the operator, substantially as herein described. 95

In testimony whereof I have affixed my signature.

ERNEST CANNING.
